PARTITION COOLING UNIT

Hermann J. Krackowizer, Chicago, Ill.

Application October 30, 1939, Serial No. 301,883

7 Claims. (Cl. 62—102)

My invention relates to refrigerated compartments and the cooling facilities therefor and has reference more particularly to the provision of cooling facilities in the form of a unit which is mounted in the compartment, preferably at a place least accessible for storage, so as to serve as a partition by which the compartment is divided into more or less separate storage spaces each of which is subjected to the cooling effect of the cooling unit.

The principal objects of my invention are to provide an improved cooling unit and arrangement thereof in a compartment; to utilize the cooling unit as a partition for dividing the compartment into separate sections; to subject each section to the cooling action of the cooling unit; to permit differential cooling of said sections; and to permit incorporation of the cooling unit in the compartment in an inconspicuous manner, these and other objects being accomplished as pointed out hereinafter and as shown in the accompanying drawings, in which,

Fig. 1 is a perspective view of a refrigerator with portions of the walls broken away to disclose the partition unit therein;

Fig. 2 is an enlarged fragmentary detail sectional view on the line 2—2 of Fig. 1 but showing the parts unassembled;

Fig. 3 is a side view of the cooling unit with the side panel removed and the lower end in section;

Fig. 4 is a front view of the cooling unit with the front panel removed;

Figs. 5, 6 and 7 are detail transverse sectional views of the lower end of the cooling unit showing a modification thereof;

Fig. 8 a vertical longitudinal sectional view of a beer cooler or the like having my invention incorporated therein;

Fig. 9 a sectional view taken substantially on the line 9—9 of Fig. 8;

Fig. 10 is a detail section view, slightly enlarged, taken on the line 10—10 of Fig. 9; and

Fig. 11 is a detail view showing a double valve arrangement for the cold air outlet.

Referring to the drawings in which I have shown several illustrative embodiments of my invention, Fig. 1 shows a refrigerator cabinet having insulated walls forming a closed compartment 11 for food storage or the like, the front wall 12 being provided with openings permitting access to the compartment and closed by doors 13 at one side of the central mullion 14 and one or more doors 15 at the other side thereof.

Midway between the ends of the compartment and behind the mullion 14 is the cooling unit, indicated as a whole at 16, which is of a flat type extending substantially from the mullion 14 to the rear wall 17 of the compartment and from a point near the bottom of the compartment near to the top thereof so as to serve in effect as a partition dividing the compartment 11 into two storage spaces, one of which is accessible through the doors 13 at one side of the mullion 14 and the other of which is accessible through the one or more doors 15 at the other side of said mullion. Either or both of said storage spaces may be provided with shelves (not shown) if required for the particular purpose for which the refrigerator is to be used and these shelves may be supported in any convenient manner as for example by any well known form of mounting strips 18 at suitable locations on the walls which are preferably of a type permitting adjustment of the shelves to selected elevations.

The cooling unit which is shown in detail in Figs. 3 and 4 is preferably of blower type comprising an outer shell or casing containing conventional cooling coils 19 in contact with which air is circulated by a fan 20 downwardly through the casing and discharged from the casing at the lower end thereof. This casing comprises front and rear panels 21 and 22 respectively to which side panels 23 are removably secured in any convenient manner, for example as shown in Fig. 2 by self threading screws 24 engaged through openings 25 in the side panels 23 and threaded into openings 26 of turned flanges 27 of the front and rear panels 21 and 22, the side panels 23 being preferably formed with flanges 28 along their lateral edges which in the assembled structure overlap the margins of the front and rear panels 21 and 22 as will be apparent from Fig. 2.

Each panel 21 and 22 has a mounting flange 29 near the upper end and these mounting flanges are seated upon and secured to mounting brackets 30 on the mullion 14 and back wall 17 respectively for supporting the cooling unit in the compartment and the coils 19 are engaged at their opposite ends through plates 31 which have outwardly lower ends 32 secured to brackets 33 on the end panels 21 and 22 as shown in Fig. 3 for supporting the coils on said panels. At their upper ends the plates 31 have inclined portions 34 extending outwardly to the respective panels 21 and 22 to deflect the circulated air downwardly between the plates 31 where the coils 19 are provided with fin plates 35 for rapid heat exchange. The upper ends of the side panels 23 are bent

outwardly as shown at 36 in Fig. 4 to provide the cooling unit casing with a flared upper end of suitable width to accommodate the fan 20 by which air is circulated downwardly through the cooling unit casing, the upper end of the cooling unit casing being closed by a top wall 37 which has an opening 38 therethrough through which the fan discharges. The fan is operated by a motor 39 which is mounted on the top wall 37 by a bridging 40 having a band 41 secured thereto surrounding the fan 20, braces 42 also being provided on the band 41 and secured to the top wall intermediate the points of attachment of the band to the bridging 40, and it will be understood that the cooling unit 16 terminates sufficiently below the top wall of the compartment 11 not only to afford ample clearance for the motor 39, but also to permit free access of air from the compartment spaces at opposite sides of the cooling unit to the fan opening 38.

Compressed refrigerant is supplied through a supply pipe 43 and expansion valve 44, located in the casing 16 to the coils 19 which have a return pipe 45 leading therefrom, and the ends of these pipes 43 and 45 are extended through the rear panel 22 of the casing 16 and provided with couplings 43^a and 45^a respectively by which suitable connection is made with the usual refrigerant compression and supply equipment (not shown) which may be located outside of the refrigerator cabinet.

The lower end of the cooling unit casing 16 is closed by a bottom wall 46 which has upturned margins 47 so that it serves as a drip pan for collecting condensation from the coils 19 which is discharged from the pan 46 through a drain pipe 48 which may lead to any convenient place of disposal, and in order to discharge the cooled air from the cooling unit 16 to the compartment spaces at opposite sides thereof the lower ends of the side panels 23 may be provided with a series of vertically elongated openings 49 extending upwardly a suitable distance above the margins of the pan 46 as shown in Fig. 1 or the side panels 23 may terminate a sufficient distance above the margins of the pan 46 to leave discharge openings 50 at opposite sides of the casing 16 and these openings may be covered by screens 51 as shown in Figs. 3 and 4. To insure uniformity of distribution of the cooled air through the cooling unit outlets 50 an inverted V-shaped deflector 52 is provided which extends from end to end of the bottom wall 46 as shown in Figs. 3 and 4.

Other forms of deflector may be employed as for example as shown at 53 in Figs. 5, 6 and 7 wherein the deflector extends from front to rear of the casing 16 and is provided with an apertured ear 54 at each end by which the deflector is bolted or otherwise secured to the front and rear walls 21 and 22. By providing these walls 21 and 22 with suitable bolt holes 55, 56 and 57, the deflector 53 may be selectively located in the three optional positions shown respectively in Figs. 5, 6 and 7 in the first of which the air is distributed equally through the opposed openings 50 whereas in Fig. 6 the air is directed toward and through the opening 50 at the right and in Fig. 7 is directed toward and through the opening 50 at the left.

Such selective arrangement is desirable not only to intensify the cooling in the selected side of the compartment but it also minimizes air movement in the other compartment and prevents dehydration of articles therein which is caused by air circulation while at the same time

there is sufficient air movement and proximity of the compartment to the cooling unit to insure a cold condition in that compartment. Thus the compartment space at the one side may be used for goods susceptible to dehydration while the other side into which the air is deflected by the Fig. 6 or Fig. 7 arrangement of the deflector 53 may be used for goods that are not susceptible to dehydration or which are desired to be more intensly cooled than those in the other side.

Referring now to Figs. 8, 9 and 10 which show my invention embodied in a beer cooler or the like, the reference numeral 58 indicates the cooler cabinet which is of elongated form with insulated walls throughout except at the top which is closed by a pair of sliding doors 59 which overlap at the center of the cabinet as shown in Fig. 8, these doors being mounted in guides 60 along which they slide to the open and closed positions thereof.

A cooling unit 61 similar to that previously described is located in an upright position midway between the ends of the cabinet so as to divide the compartment into two cooling spaces, both of which are exposed to the cooling effect of the cooling unit 61.

This cooling unit is relatively short as compared with the previously described cooling unit 16 and preferably thicker to accommodate extra width for cooling coils 62 and has side panels 63 with attaching flanges 64 at the ends secured directly to the front and rear walls of the cabinet. Front and rear panels, corresponding to the panels 31 of the previous cooling unit 16 are thus dispensed with and the end plates 65 through which the opposite ends of the coils 62 project and by which the coils are supported are formed at their upper ends with outturned portions 66 which are secured to said cabinet walls, the lower ends of said plates 65 being turned outwardly as shown at 67 to close the lower ends of the spaces between the plates 65 and the respective walls to which said plates are attached.

The upper ends of the side plates 63 are bent outwardly slightly as shown in Fig. 8 to provide a flared upper end which is closed by a top plate 68 and this top plate has an opening 69 therethrough over which a fan 70 and motor 71 are mounted on the top plate 68 in the same manner as the fan 20 and motor 39 are mounted in the previously described cooling unit 16, the fan being likewise surrounded by a band 72 and operable by the motor 71 to discharge air downwardly into and through the casing of the cooling unit 61.

Like in the previous cooling unit 16, a pipe 73 supplies compressed refrigerant through an expansion valve 74 to the coils 62 which have a return pipe 75 leading therefrom and these pipes 73 and 75 have couplings 73^a and 75^a at their ends for connection with pipes 73^b and 75^b respectively which lead therefrom through the rear wall of the compartment to refrigerating equipment which compresses and supplies refrigerant to the coils 62 in the usual manner.

The bottom 76 of the beer cooler compartment slopes downwardly to the center of the compartment as shown in Fig. 8 for drainage purposes and has a drain outlet 77 at the low center and the cooling unit 61 has an open bottom which is elevated sufficiently above the low central portion of the compartment bottom to permit free outflow of the cooled air from the cooling unit.

Perforated or screen panels 78 are provided at opposite sides of the cooling unit 61 to support

the bottles of beer or other articles to be cooled in the compartment spaces, these panels being supported above the compartment bottom 76 by angle irons 78 on the compartment end walls and brackets 80 on the compartment front and rear walls near the cooling unit 61 and it will be noted that the inner ends of the panels 78 are above the lower end of the cooling unit 61 so that the cold air from the cooling unit is discharged into the space between the panels 78 and the bottom 76 of the compartment. By reason of the upward slope of the bottom 76 from the center of the compartment to the ends and the screens or perforated panels 78 which support the compartment contents above the bottom, the cooled air is spread outwardly toward the ends of the compartment and distributed quite uniformly through the screen or perforated panel openings to the compartment thereabove.

In beer cooling it is desirable to provide two 26 cooling compartments, one of which serves as a pre-cooling compartment and in the other of which fully cooled beer ready to serve may be kept separate from new supplies which are in the process of cooling and the interposition of the cooling unit 61 midway between the ends of the beer cooler affords two separate compartments which are useful for this purpose. Moreover it is desirable to intensify the cooling in the pre-cooling compartment and for convenient accomplishment of this purpose, I have provided in the bottom of the compartment directly under the cooling unit 61 a damper 81 which extends from the front wall of the compartment to the rear wall thereof and is pivoted along its central axis to said walls as indicated at 82 to swing from the position shown in full lines in Fig. 8 to the dotted line position 81^a of said figure. This damper is of sufficient width and properly mounted between the lower end of the cooling unit 61 and the bottom of the compartment to substantially close off air discharge from the cooling unit to either selected end of the compartment and direct the cooled air supply to the other end so that the latter end is more intensely cooled and either end of the compartment may accordingly be used as the storage space from which to serve the fully cooled beer while the other end of the compartment may be used for pre-cooling.

Thus with the damper 81 arrangement as shown in Fig. 8 the compartment at the left end would be used for the fully cooled ready to serve beer while a new supply is being cooled in the compartment at the right end of the cooler and after the fully cooled supply is exhausted from the left end compartment, the damper 81 would be adjusted to the dotted line position 81^a in which the cooling would then be intensified in the left end compartment and the beer would then be served from the right end compartment while the compartment at the other end was refilled and the new supply pre-cooled. Each end compartment has an individual door 59 so that access may be had to either selected compartment without substantial wastage of cold from the other compartment and it will be understood that since the cold air is being supplied to the pre-cooling compartment, the circulation of cold air from the cooling system is more or less localized within that compartment, thus avoiding wastage of cold air from the cooling system through the door to the other compartment which is opened from time to time as the beer is served.

For convenience in adjusting the damper 81, 75

the latter has a stem 83 fixed thereto at one end and projecting through the front wall of the cabinet with an operating handle 84 on the other exposed end by which the damper is adjusted, and this handle by its position serves also to show the position of adjustment of the damper 81.

Other forms of dampers or valves may be employed to control the supply of cooled air to the compartment spaces at the opposite sides of the cooling unit, for example as shown in Fig. 11 wherein two valves 85 are employed with their inner edges in close adjoining relation and pivoted at the opposite ends of their respective inner edges to the front and rear walls of the cabinet, and each valve 85 preferably has a pivoting stem extending through the front wall and provided with an operating handle similar to the stem 83 and handle 84 of the damper 81 so that each damper or valve 85 is independently adjustable.

The inner edges of the dampers or valves 85 are pivoted substantially midway between the bottom of the compartment and the lower end of the cooling unit so that when both dampers 85 are swung downwardly with their outer edges lying against the compartment bottom they form an oppositely inclined deflector affording equalized distribution of air from the cooling unit to the two compartment spaces at the opposite sides thereof. Either damper 85 may be closed against the lower end of the cooling unit to discharge the cooled air outflow from the cooling unit selectively to either compartment space or these dampers may be adjusted to intermediate positions to vary the relative amount of cooled air supplied to the compartment spaces.

While I have indicated herein that in the illustrated embodiments the air is circulated downwardly through the cooling unit and such direction of circulation is usually preferred, the fan may be operated to circulate the air upwardly if desired or may be reversible for selective circulation of the air in either direction at will.

While I have shown and described my invention in a preferred form, I am aware that various changes and modifications may be made therein without departing from the principles of my invention, the scope of which is to be determined by the appended claims.

I claim as my invention:

1. In a refrigerator, the combination of a walled enclosure with a cooling compartment therein, means in the compartment comprising an upright hollow partition like housing which separates one portion of the compartment from another portion thereof, said housing being spaced from the top of the compartment and having a fan mounted on the upper end and operable to withdraw air from each compartment and discharge same downwardly through the housing, means at the lower end of the housing permitting discharge of air from the interior of the housing into the aforesaid portions of the compartment, said means including a valve adjustable to control the air supply to said portions, means at the exterior of the compartment for adjusting said valve, and cooling coils in the housing in the path of air circulation therethrough.

2. In a beer cooler, or the like, the combination of an enclosure forming an elongated compartment having a top including a pair of overlapping sliding doors, an upright housing constituting a combined partition and cooling unit disposed vertically below the overlapping inner ends of said doors and dividing the compartment into separate chambers each accessible through one of the

doors, air cooling means within and carried by the housing and a fan carried by the cooling unit and operable to circulate air from each chamber through the cooling unit in contact with the air cooling means and back to said chambers, said combined partition and cooling unit being self-contained and insertible as a whole.

3. In a beer cooler, or the like, the combination of an enclosure forming an elongated compartment, an upright partition like cooling unit in the compartment between the ends thereof dividing the compartment into separate chambers, and a fan associated with the cooling unit and operable to circulate air from each chamber through the cooling unit and back to said chambers, a perforate panel at each side of the cooling unit and elevated above the bottom of the compartment, and valve means at the lower end of the cooling unit and operable to selectively discharge the air from the cooling unit into the compartment space below either panel, each said compartment spaces having the bottom walls thereof below the panel sloped upwardly to the outer end of the respective compartment space so as to gradually diminish such compartment space and equalize the distribution of air discharge through the respective panel throughout the area thereof.

4. In a refrigerator, the combination of a walled enclosure with a cooling compartment therein, means in the compartment comprising a hollow partition like housing which separates one portion of the compartment from another portion thereof, said housing having spaced inlet and outlet means, providing inlet and outlet communication thereof with each of said compartment portions, cooling coils in the housing between said openings, and a blower operable to circulate air through the housing in contact with the coils from the inlet means to the outlet means, said outlet means including a pair of valves positionable in oppositely inclined relation to provide a deflector by which the air is distributed equally to said compartment portions and each valve being independently adjustable to selectively regulate the air supplied to said compartment portions.

5. A refrigerator having a cooling chamber, and a combined cooling and partition unit dividing the chamber into opposite compartments, said unit including a housing supported within the chamber, spaced from a pair of confronting walls thereof and in communication at its top and bottom with each compartment, cooling coils carried by and within the housing, and a blower carried by the housing for circulating air from

the compartments into the housing and through the housing in contact with the coils, and then out of the housing and into each compartment, said combined cooling and partition unit being self-contained and insertible as a whole with respect to the cooling chamber.

6. In a refrigerator, the combination with an enclosure having a cooling compartment, of a self-contained combined partition and cooling unit within and dividing the compartment into opposite sections and insertible and removable as a unit, said unit comprising cooling coils, an upright closed housing terminating at its top short of the top of the compartment and having air flow openings at opposite ends thereof, the walls of the housing forming a channel enclosing said coils and constructed to direct a current of air from said opening across the coils, a blower mounted on the housing and positioned to affect a flow of air from opposite sides of the housing through one of the air flow openings into the housing and across the cooling coils therein and out through the air flow opening at the opposite end of the housing, a substantially horizontal perforate panel within each cooling compartment section and supported above the bottom of the compartment and at a higher level than the lower air flow opening of the housing, and deflector means for directing the flow of air from the bottom of the housing selectively to opposite sides of the housing and beneath the perforate panels.

7. In a refrigerator, the combination with an enclosure having a cooling compartment, of a self-contained combined partition and cooling unit within the compartment and dividing the same into opposite sections and comprising cooling coils, an upright housing flared outwardly and upwardly and provided in its top wall with an air flow opening of greater width than that of the unflared housing portion, the walls of the housing forming a channel enclosing said coils and constructed to direct a current of air from said opening across the coils, opposite side walls of the housing having air flow openings at the bottom of the housing, the top of the housing terminating short of the top of the cooling compartment, a blower mounted upon the top wall of the housing in position to affect a flow of air from opposite sides of the housing and into the housing through the air flow opening at one end of the housing and across the cooling coils therein and out through the air flow opening at the opposite end of the housing.

HERMANN J. KRACKOWIZER.
